UNITED STATES PATENT OFFICE.

CHARLES T. MCCUE, OF HARTFORD, CONNECTICUT.

DESIGN FOR A STAY-END.

SPECIFICATION forming part of Design No. 33,783, dated December 25, 1900.

Application filed November 20, 1900. Serial No. 37,183. Term of patent 7 years.

To all whom it may concern:

Be it known that I, CHARLES T. MCCUE, a citizen of the United States, and a resident of Hartford, in the county of Hartford and 5 State of Connecticut, have invented and produced a new and original Design for a Stay-End Applicable for Use in the Running-Gear of Vehicles, of which the following is a specification, reference being had to the accompanying drawings, forming part thereof.

Figure 1 is a side view of a stay-end, showing my new design. Fig. 2 is an end view of the same. Fig. 3 is a bottom view.

As shown in the drawings, the leading or 15 material feature of my design consists of a body portion *a*, that when viewed in side elevation or in plan presents a long appearance as compared with its breadth or thickness. This body portion has at one end a projection

b, extending in a direction at an angle to the axis of the body portion. This projection when viewed from the end, as shown in Fig. 3, is of rectangular form; but at its junction with the body portion *a* there are formed lateral projections *c*. These projections *c* are 25 of curved form when the stay-end is viewed in side elevation, as shown in Fig. 1, forming recesses *c'* when seen from the under side, as shown in Fig. 3.

What I claim as my invention, and desire 30 to secure by Letters Patent, is—

The design for a stay-end as herein shown and described.

CHARLES T. MCCUE.
